UNITED STATES PATENT OFFICE.

JOHN E. HILL, OF ST. LOUIS, MISSOURI, ASSIGNOR TO AMERICAN ROLL PAPER COMPANY, OF ST. LOUIS, MISSOURI, A CORPORATION.

ROLL-PAPER HOLDER.

No. 802,145.

Specification of Letters Patent.

Patented Oct. 17, 1905.

Application filed June 5, 1905. Serial No. 263,739.

To all whom it may concern:

Be it known that I, JOHN E. HILL, a subject of the King of Great Britain, residing in the city of St. Louis, in the State of Missouri, have 5 invented certain new and useful Improvements in Roll-Paper Holders, of which the following is a full, clear, and exact description, reference being had to the accompanying drawings, forming part of this specification.

10 My invention relates to a roll-paper holder constructed for the mounting of the roll of paper in a vertical position, the device being more particularly intended for use in connection with the larger sizes of rolls of paper 15 which it is inconvenient to mount in a horizontal position.

Figure I is a top or plan view of my roll-paper holder with a roll of paper mounted therein. Fig. II is a side elevation of the 20 holder. Fig. III is a top view of the central portion of the base of the holder. Fig. IV is a perspective view of the forward end of the upper paper-roll-spindle receiving-arm and the spindle-retaining yoke carried by said arm.

25 The base of my roll-paper holder consists of a plurality of radially-arranged arms 1, that extend from a central hub 2, provided with a socket 3. Mounted upon the hub 2 is a lower bearing-plate 4, that contains a circular race-way 5 in its upper side which receives bearing-balls 6. The lower bearing-plate is provided with a central aperture.

7 is an upper bearing-plate that is mounted upon the lower bearing-plate and fitted thereto. This upper bearing-plate is provided at 35 its lower side with a downwardly-extending spindle 8, that passes through the aperture in the lower bearing-plate and rests in the socket 3 of the base-hub 2. At the upper side of the 40 upper bearing-plate is a socket 9.

10 is a turn-table secured to and surmounting the upper bearing-plate and preferably of greater dimensions than said plate. This turn-table receives the roll A of paper, which 45 is seated thereon in upright position and is held in such position by the usual rod B, passing longitudinally through the roll of paper and resting in the socket 9 of the upper bearing-plate.

50 11 designates an upright bar secured to one of the base-arms 1 and extending vertically in alinement with the roll of paper.

12 is an arm fixed at its outer end to the

upper end of said upright bar. This arm 12 extends horizontally across the upper end of 55 the holder to a position directly above the axis of the turn-table 10, and it has in its forward end a notch 13, adapted to receive the upper end of the rod B, passing through the roll of paper. Projecting upwardly from the 60 upper side of the arm 12 and located at the sides of the notch 13 is a pair of wings 14.

15 is a retaining-yoke of U shape that is 65 swingingly connected to the wings 14 by a pivot-bolt 16, which passes transversely through the arms of said yoke and said wings. This yoke is adapted to be elevated into the vertical position seen in dotted lines, Fig. IV, to permit of the introduction of the rod B into the notch 13 of the arm 12, and then it is lowered into the horizontal position seen in full lines, Figs. I, II, and IV to retain the rod in 70 in said notch.

17 designates the cutting-knife, which is carried by arms 18, movably connected to the 75 upright bar 11 for swinging movement relative to the axis of the roll of paper. These arms are actuated by springs 19, which serve to hold the knife 17 pressed against the roll 80 of paper.

When my roll-paper holder is in service, the roll of paper is supported by the turn-table 10, and this turn-table rotates freely as the roll of paper is revolved in withdrawing paper therefrom, due to the turn-table having 85 the central bearings furnished by the upper and lower bearing-plates on which it is supported.

I claim as my invention—

1. In a roll-paper holder, the combination 90 of a base, a turn-table mounted upon said base, an upright secured at its lower end to said base, a horizontal slotted arm secured to the upper end of said upright and arranged to receive a rod passing through the roll of paper, and a yoke pivoted to said arm and arranged to be swung over a rod passing through a roll of paper mounted on said turn-table, substantially as set forth.

2. In a roll-paper holder, the combination 100 of a base, a lower bearing-plate surmounting said base, an upper bearing-plate fitted to said lower plate, a turn-table carried by said upper plate, an upright secured to said base, a slotted horizontal arm at the upper end of 105 said upright adapted to receive a rod passing

vertically through a roll of paper, and a yoke pivoted to said arm and arranged to be swung over said rod, substantially as set forth.

3. In a roll-paper holder, the combination
5 of a base having a hub provided with a socket,
a lower bearing-plate mounted on said hub,
an upper bearing-plate seated on said lower
bearing-plate and having a spindle extending
through the lower plate into the socket in said
10 hub, a turn-table carried by said upper bearing-plate, an upright secured to said base, a

slotted horizontal arm secured to the upper end of said upright and adapted to receive the upper end of a rod passing vertically through a roll of paper seated on said turn-table, and 15 a yoke pivoted to said arm and arranged to be swung over said rod, substantially as set forth.

JOHN E. HILL.

In presence of—

NELLIE V. ALEXANDER,
BLANCHE HOGAN.
